AUTOMATIC PHONOGRAPH

Carl W. Sundberg, Bloomfield Hills, Mich., assignor to
Seeburg Corporation, a corporation of Illinois

Application November 3, 1958, Serial No. 53,254

Term of patent 14 years

(Cl. D56—4)

Fig. 1 is a front perspective view of an automatic phonograph showing my new design;

Fig. 2 is a reduced front elevational view thereof;

Fig. 3 is a reduced left side elevational view thereof, the right side elevational view being substantially a mirror image thereof; and

Figure 4 is a reduced top plan view thereof.

The dominant features of the design reside in the portions shown in full lines.

I claim:

The ornamental design for an automatic phonograph, as shown and described.
